UNITED STATES PATENT OFFICE.

CHARLES E. ANDERSON, OF SIOUX FALLS, SOUTH DAKOTA.

CIGARETTE HOLDER.

Application filed March 17, 1924. Serial No. 699,935.

To all whom it may concern:

Be it known that I, CHARLES E. ANDERSON, a citizen of the United States, residing at Sioux Falls, in the county of Minnehaha 5 and State of South Dakota, have invented certain new and useful Improvements in Cigarette Holders; and I do declare the following to be a full, clear, and exact description of the invention, such as will enable others skilled in the art to which it appertains to make and use the same.

My invention relates to improvements in cigarette holders of the type embodying a finger-ring and a cigarette holding clamp 15 thereon, such devices being advantageous for numerous reasons, as they allow the fingers of the hand holding the cigarette to be entirely free for use.

The principal object of the invention is to 20 provide an extremely simple and inexpensive device of the class set forth, in which the clamp for the cigarette, is held in operative position by a clamp-applying member which engages the finger upon which the 25 ring is placed.

With the foregoing in view, the invention resides in the novel subject matter hereinafter described and claimed, the description being supplemented by the accompanying 30 drawing.

Figure 1 is a perspective view showing the use of the invention.

Figure 2 is a vertical sectional view.

Figure 3 is a vertical section at right angles to Fig. 2, as indicated by lines 3—3 35 thereof.

In the form of construction selected for illustration in the present application, a finger-ring 1 is provided, having two ends 40 bent laterally outward to form ears, as indicated by the numerals 2. Secured to these ears, I have shown a shank 3 carrying a curved jaw 4 to contact with one side of a cigarette, while pivoted at 5, between the 45 ears 2, is a second shank 6 carrying a second curved jaw 7 to engage the other side of the cigarette. Extending laterally from the lower end of the shank 6, a clamp-applying arm 8 has been shown, said arm being adapt- 50 ed to contact with the finger upon which the ring 1 is placed, so as to swing the clamp jaw 7 inwardly toward the jaw 4 and hold the cigarette firmly in place.

When the use of the device is not needed, it is removed from the finger and the arm 55 8 is thus released to free the jaw 7, thus permitting the cigarette butt to drop from the device.

The article is exceptionally simple and inexpensive, yet is very desirable, and as 60 excellent results have been obtained from the details disclosed, such details are preferably followed. However, within the scope of the invention as claimed, numerous minor changes may be made.

I claim:

1. In a cigarette holder comprising a clamp for the cigarette and a finger-ring carrying said clamp; a clamp-applying member operatively associated with said clamp and adapted to contact with the finger upon which the ring is placed, to hold said clamp in operative position.

2. A cigarette holder comprising a finger-ring having relatively fixed and movable cigarette-holding jaws, and a clamp-applying member connected with one of said jaws and extending laterally from said finger-ring to move said one jaw toward the other jaw, said member being adapted to contact 75 with the finger upon which the ring is placed.

3. A cigarette holder comprising a finger-ring, a stationary jaw projecting therefrom, a movable jaw co-operable with said stationary jaw in holding a cigarette, means pivotally mounting said movable jaw on said ring, and an arm extending from said movable jaw and adapted to contact with the finger upon which the ring is placed, whereby to hold said movable jaw in operative 90 position.

4. A cigarette holder comprising a ring having a pair of spaced radial ears, a stationary jaw having a portion secured to said ears, a movable jaw having a shank pivoted between said ears, and an arm extending laterally from said shank and adapted to contact with the finger upon which the ring is placed to swing said shank to a position 100 to apply said movable jaw.

In testimony whereof I have hereunto affixed my signature.

CHARLES E. ANDERSON.
